UNITED STATES PATENT OFFICE

VINCENT G. APPLE, OF DAYTON, OHIO

TOOL FOR MAKING ARMATURES

Original application filed May 16, 1929, Serial No. 363,702. Divided and this application filed August 15, 1930. Serial No. 475,483.

This invention is a division of my copending application, Serial No. 363,702, filed May 16th, 1929, and relates to a tool for making armatures of the class comprising a slotted core, a winding of insulation covered wire and a commutator.

An object of the invention is to facilitate the assembly of an armature of this type.

A more specific object is to provide a tool for making a structure wherein the core, the turns of the wire composing the winding and the bars composing the commutator are all imbedded in the same substantially continuous mass of impervious insulating material whereby they are permanently held in spaced relation and protected against the harmful effect which results when oil, moisture, or other foreign matter is permitted to enter into the spaces between the conductive portions of the structure as they are in common practice.

Other objects and meritorious features of the invention will become apparent to one skilled in the art as the invention is described in detail and reference is made to the drawings wherein,

Fig. 1 shows the core of the armature which I have selected to illustrate my invention.

Fig. 2 shows the core Fig. 1 with the slots lined with sheet insulation preparatory to placing the winding thereon and with collars at the ends of the core to keep the winding spaced apart from the shaft as it is being placed.

Fig. 3 shows the winding in place with extending leads formed of the ends of the wire composing the coils.

Fig. 4 shows a bar of stock from which the commutator segments are made.

Fig. 5 shows a single commutator segment.

Fig. 6 shows the wound structure Fig. 3 with a segment Fig. 5 electrically joined to each lead.

Fig. 7 is a vertical axial section through a tool used to arrange the segments of the structure Fig. 6 in proper spaced relation.

Fig. 8 shows the tool Fig. 7 in perspective.

Fig. 9 is a ring for holding the segments to the tool Fig. 6.

Fig. 10 shows the tools Figs. 7 and 9 assembled on the armature to locate the commutator segments.

Similar numerals refer to similar parts throughout the several views.

In the drawings a shaft 16 having a longitudinally extending keyway 17 carries a core 18 composed of a plurality of core laminæ 19. Laminæ 19 have a series of winding slots 20 separated by teeth 21, and integral keys 22 extend inwardly into keyway 17 whereby slots 20 are held in definite relation to keyway 17.

Slots 20 are lined as in Fig. 2 by placing a single strip of insulation 23 around the core 18 and looping it downward into each slot as at 24. Collars 26 and 27 are placed over the shaft 10, but remain there only while the winding is being put on the core.

Fig. 3 shows the core 18 with the coils 28 wound in place. But before winding the wire into coils it is preferably treated by saturating the covering of the wire with liquid insulation, to insure that the pressure incident to the subsequent molding operation 75 will not break down the insulation between adjacent turns. Leads 29 are formed by joining the end of one coil to the beginning of the next as in common practice.

In Fig. 5 I show one of the segments 30 which I use to compose a commutator. To make these segments I provide wire of trapeziform cross section (see Fig. 4) and cut it into lengths by cutting through the wire at an angle as at 25. Thus for each cut there is produced a segment 30 having one end beveled as at 31 and the other end as at 32. A lead slot 33 is then easily cut through the corner of each segment as shown.

Fig. 6 shows the structure after a segment 30 has been joined to each of the leads 29. The leads are pressed into the lead slots 33 whereupon they may be arc welded, brazed, soldered or otherwise electrically joined to the segments.

After all of the segments are joined to the leads, a method of composing a commutator from the segments is provided. This consists briefly of holding the segments in the exact spaced relation which they occupy in 100

the finished commutator and molding insulation within, between and about them while so held, hardening the insulation, then removing the holding means, and, since it is one of the objects of the invention to have the same substantially continuous mass of impervious insulation bind the segments together and extend round about the windings to enclose them, the tools are made to accomplish this object.

Fig. 7 is a vertical axial section through the tool 34 into which the segments 30 are temporarily assembled in order that they may be more easily entered into the mold. The tool consists of a cylindrical body 35 bored at 36 and counterbored at 37, with annular grooves 38 and 39 extending around it. The counterbored portion 37 is divided by a series of longitudinal cuts into prongs 40 and each prong is further milled at its outer diameter from the free end to groove 38 to provide an integral key 41 extending outwardly therefrom. A plug 42, bored at 43 is fitted into opening 36 and secured by pin 44. Another pin 45 extends inwardly into opening 43. Tool 34 is also shown in perspective in Fig. 8.

When an armature has been wound, and has its commutator segments 30 connected to the leads 29 as shown in Fig. 6, the collar 27 is removed and the tool 34 is placed over shaft 16 with pin 45 in keyway 17 of the shaft. The segments 30 are then laid around the tool with keys 41 of the tool extending outwardly between the segments as in Fig. 10. By this means the segments are held spaced apart and in correct relation to the winding slots 20 of core 18. Ring 46, Fig. 9 is now forced over the outside of segments 30, the prongs 40 springing slightly inward to permit the ring to go over, and the structure appears as in Fig. 10 and after removal of collar 26 is ready to have a body of insulation molded about the winding and commutator segments.

In my copending application Serial Number 363,702, filed May 16th, 1929, of which this application is a division, I show, describe and claim a completed armature and the method of making it, said method including the use of the tool herein shown and described. I therefore do not herein show the completed armature, or the method of making it, or the necessary apparatus used in making it, claims in this application being confined to the particular assembling tool herein shown and described.

Having described my invention, I claim,

1. For building armatures of the character herein described, apparatus comprising, a cylinder having an axially extending opening adapted to receive the armature shaft, locating means extending into said opening adapted to enter the keyway in said shaft, and locating means on the outside of said cylinder

adapted to temporarily hold each segment in the position it will afterwards occupy in the commutator.

2. For building armatures of the character herein described, apparatus comprising, a cylinder having means for holding it in axial alignment with the armature core, locating means on its outside diameter adapted to hold the commutator segments in proper spaced relation, and means on said cylinder to align said locating means in definite angular relation to the winding slots of said core.

3. For building armatures of the character herein described, apparatus having means to locate it in axial alignment with the core, a plurality of means capable of radial movement for locating the commutator segments in proper spaced relation, and means to align said locating means in definite angular relation to the winding slots of said core.

4. For building armatures of the character herein described, apparatus comprising, means to locate it in axial alignment with the core, a plurality of means capable of radial movement for locating the commutator segments in proper spaced relation, means offering resilient resistance to said radial movement, and means to align said locating means in definite angular relation to the winding slots of said core.

In testimony whereof I affix my signature.

VINCENT G. APPLE.
